W. G. Charles

ATTORNEY.

UNITED STATES PATENT OFFICE.

SHERMAN R. COLLINGWOOD, OF WICHITA, KANSAS.

ROLLING RADIATOR SHUTTER.

1,421,174.

Specification of Letters Patent. Patented June 27, 1922.

Application filed January 17, 1921. Serial No. 437,842.

To all whom it may concern:

Be it known that I, SHERMAN R. COLLINGWOOD, a citizen of the United States, and resident of Wichita, in the county of Sedgwick and State of Kansas, have invented certain new and useful Improvements in Rolling Radiator Shutters, of which the following is a full, clear, and exact description.

10 My invention relates to that class of attachments for automobile-radiators, in which a flexible curtain is arranged to be rolled upon a spring-actuated roller, and to cover all or any part of the anterior surface of the 15 radiator, for prevention of over-cooling of the motor in cold weather; also, to prevent freezing of the radiator water where no anti-freeze mixture is employed.

20 My invention provides means whereby the shutter or curtain is adjustable to any desired position from the front seat of the car, by pulling or paying out a chain.

25 The preferred construction of the device is illustrated in the accompanying drawings, in which—

Fig. 1 is a side elevation, the top of the engine-hood being broken away; Fig. 2 is a front elevation; Fig. 3 shows the front pulley; Fig. 4 is an end elevation of the 30 spring-roller, and its housing in section; Fig. 5 is a detail sectional view of the roller-spring and a portion of the curtain; Fig. 6 is a detail section of the chain-fastening device; Fig. 7 is a detail section taken on 35 line VII—VII on Fig. 6; and Fig. 8 is a rear view of the adjusting means as seen from the front seat of the car.

On Fig. 4, a housing 1 is shown as secured to a horizontal apron 2 of a motor car, at the 40 bottom of the radiator 3. In one end of said housing is a bearing-lug 4, having an angular slot 5 therein, to receive the squared end 7' of a spindle 7, inserted in the hollow end of the roller 6, which has a gudgeon (not 45 shown) on its other end, rotatable in a bearing, not shown. A helical spring 8 has one end secured to the spindle at 9, and the opposite end is secured to the roller 6, as for example by insertion through a perforation 50 in the roller as at 10.

To shed water, snow or dust, the upper lip

of the housing nearly touches the radiator. The curtain 12 is fastened to roller 6 and passes up between said lip and the radiator, being long enough to cover the radiator 55 front when fully extended. A cable 14 is connected to the curtain at 15 (Fig. 2) and passes over a small grooved pulley 16, being connected at c with a chain 14', which is passed through a hole 18 in the dash 19. 60

The front pulley, 18, has a yoke 20 secured to the front of the radiator in any preferred manner. The second roller, 17, has its yoke in the form of a clip 21, which is mounted on the radiator-tie-rod 22 and held 65 either by friction or by a set-screw.

The opening 18 through the dash 19 is provided with a metal plate 23, having an opening in register with that in the dash. This plate has an integral upstanding lug 70 24, small enough to enter freely the opening of any link in the chain 14. To adjust the curtain or shutter, either up or down, the operator disengages the chain from lug 24 and either pulls or pays it out, the spring 75 causing the motion in the latter case, and the chain slipping easily through the apertures. When the curtain is at the desired height the chain is hooked over the lug, which holds it in place against the tension of the 80 roller spring.

The details here shown may be modified without sacrificing any of the advantages of the invention.

Having described my invention, I claim 85 and desire to secure by Letters Patent:

The combination, with the radiator, tie-rod and dash of a motor-car, of a vertically slideable rolling shutter positioned closely in front of the radiator, a spring-actuated 90 roller attached to said shutter, a cable attached to the top of said shutter, a chain connected to said cable, a forward guide-pulley having a shank inserted in the front of the radiator near the top of the same, a 95 rear guide-pulley having a clip mounted on said tie-rod and means for adjusting the chain on the dash.

SHERMAN R. COLLINGWOOD.
